UNITED STATES PATENT OFFICE.

GEORGE H. GILLIGAN, OF PROVIDENCE, RHODE ISLAND, ASSIGNOR TO U. S. RING TRAVELER COMPANY, OF PROVIDENCE, RHODE ISLAND, A CORPORATION OF RHODE ISLAND.

SUPPORT FOR RING TRAVELERS.

Application filed January 16, 1928. Serial No. 247,014.

My invention relates to supports for ring travelers of the type wherein the spinner or twister ring is reversible and horizontal, and the traveler, circular.

5 At present a loose or broken thread carried by the operating spindle strikes against the lubricant exposed upon the inner face of the ring, thus fouling the thread on the spindle bobbin, and sometimes spotting the thread 10 upon adjacent bobbins.

An object of my invention is to prevent the above disadvantages. Other objects of my invention are to insure a perfect interengagement of the parts, and permit a facile reversal 15 of the ring, as well as afford a strong construction.

My invention, therefore, consists in the means for effecting the results above referred to.

20 In the accompanying drawings,

Figures 1 and 2 are a plan and a side elevation of my novel device,

Figure 3, a section of the same and a ring rail upon which it is mounted taken on line 25 3—3 of Figure 1,

Figure 4, a detail view of the shield member, and

Figure 5, a fragmentary enlarged section 30 of a part of my device corresponding with Figure 3.

Similar reference characters indicate similar parts throughout the views.

As herein shown 6 represents the ring rail of a spinning or twisting frame, and 7 one of 35 the usual spindle orifices.

An annular ring holder 9 is vertically split, as at 10, to form an expandable and contractible member comprising a flat annular head or rim 11, and a depending cylindrical body 40 12 integral with an intermediate portion of the head. The latter is provided in its upper face with an internal channel 13 forming a horizontal supporting face 14 and an undercut or inclined bearing face 15. The resilient body 12 is frictionally seated in the orifice 12 45 of the ring rail, and the exterior portion of the rim 11 rests upon the latter. A hori-

zontal spinning or twisting ring 17 comprises a base flange 18, an intermediate web or body 19 and a flat head or flange 20. The 50 flange 18 of the ring rests upon the face 14 in the channel 13 and is slightly overlapped by the wall or face 15, and is tightly engaged therewith by the resiliency of the holder 9.

A tubular shield member 23 consists of a 55 cylindrical lower portion 24 whose exterior tightly engages the inner face of the body 12 of the ring holder, and an inwardly and upwardly tapering or retracted intermediate shoulder portion, terminating in an upper 60 cylindrical neck or shield portion 26 extending to substantially the top of the ring 17, but laterally spaced therefrom, so that there is an annular recess or raceway 28 intermediate the wall 26 and the flange 20 for a circular traveler 30 upon said flange.

The lubricant upon the inner face of the portion 19 of the ring is thus shielded from contact with any loose or broken thread carried by the spindle or fed thereto from the 70 delivery rolls through the traveler 30.

I claim:—

1. In a support for ring travelers, an annular ring holder provided with a vertical split and with an internal channel in its upper face, a traveler ring seated in the channel and an imperforate tubular shield embraced by the holder and frictionally held therein and extending from the lower edge of the ring to approximately the horizontal 75 plane of the ring top and spaced from the ring to form a raceway for a traveler.

2. In a support for a ring traveler, a resilient annular ring holder provided with a vertical split, a traveler ring embraced by the 80 holder, and a shield comprising a cylindrical lower portion also embraced by the ring, an inwardly and upwardly tapering intermediate portion, and a cylindrical upper portion extending to substantially the maximum 85 height of the ring and spaced from the ring.

In testimony whereof I have affixed my signature.

GEORGE H. GILLIGAN.
